UNITED STATES PATENT OFFICE.

CLIFTON WEST, OF LONDON, ENGLAND.

DESIGN FOR A CONTAINER FOR GRAMOPHONE NEEDLES.

Application filed December 12, 1921. Serial No. 521,933. Term of patent 14 years.

To all whom it may concern:

Be it known that I, CLIFTON WEST, a subject of the King of Great Britain, residing at London, England, have invented a new, original, and ornamental Design for a Container for Gramophone Needles, of which the following is a specification, reference being had to the accompanying drawing, forming part thereof.

The drawing is an enlarged perspective view of the container shewing my new design.

I claim:—

The ornamental design for a container for gramophone needles as shown:

CLIFTON WEST.
